RADIO ALARM SYSTEM

James O. Howton, Freewater, Oreg., assignor to
Howton Radio Alarm Company, Seattle, Wash.

Application January 12, 1938, Serial No. 184,713

2 Claims. (Cl. 177—314)

This invention relates to alarm systems and adjuncts thereof and particularly to radio alarm systems adapted to broadcast automatically on police and fire bands so that these departments will be directly and appropriately advised of emergency conditions.

As illustrative of the invention I have shown two embodiments thereof in the accompanying drawings with reference to which description will be made in order that the principles underlying the invention may be clearly understood. According to the first embodiment, distinguishable code messages may be broadcast for direct reception by the appropriate department. According to the second embodiment a sound record is utilized for the voice broadcast of fire and/or burglar alarms.

In the drawings:

Figures 1 and 1a, taken together, constitute a diagrammatic representation of the first embodiment of the invention designed to broadcast in code for either burglary or fire.

Figure 2 is a diagrammatic representation of the second embodiment designed to broadcast voice alarms in case of fire and/or burglary.

Figure 3 is an elevational view of a fire alarm circuit relay which appears diagrammatically in Figure 1a.

Figure 4 is an elevational view of a burglar alarm circuit relay, also appearing diagrammatically in Figure 1a.

Figure 5 is a side elevation of code keying mechanism and driving motor shown diagrammatically in Figure 1.

Figure 6 is a front face view of the mechanism of Figure 5.

Figure 7 is a rear view of mechanism of Figure 5, and

Figure 8 is a face view of a sound record disc utilizable in the embodiment of Figure 2.

Referring to Figures 1 and 1a (and to Figures 3 to 7 for details) reference numeral 33 designates a crystal oscillator which drives the grid of a tube 31 of which the plate drives inductance 43, the latter being tuned for resonance by variable condenser 42. Inductance 43 drives grid 48 of a tube 46, the final amplifier, through condenser 44, capacitively coupling tube 46 to the first crystal amplifier tube 31. The plate circuit, fed by plate 62 of tube 46, drives the variable inductance 53 of a radio frequency transformer, 53, 55, inductance 53 being tuned by a variable condenser 52. The antenna and ground circuits are inductively fed to inductance 55 and receive energy from this inductance which is fed into

antenna 56 through tuning condenser 57. Inductance 55 is adjustable.

The above described transmitting circuit receives both filament and plate supply voltage from 5 alternating current transformer 9, secondary coil 19 of the transformer supplying the filament circuit of a rectifier tube 18. Plates 22 and 23 of tube 18 receive their excitation from secondary coil 21 of transformer 9 and constitute the negative side of the plate supply circuit to the transmitter above described. The filament circuit supplies positive electricity to the plates of tubes 31 and 46 through filter retards 27 and 28, these in turn being supported in this filter circuit by 10 parallel filter condensers 24, 25 and 26. The plate energization of tubes 31 and 46 is taken from resistor 29 which may be tapped for variable voltages. Transformer 9 is driven by a rotary converter or motor generator 1 which in turn is driven by a direct current battery 6. The function of motor generator 1 is to convert the energy from direct to alternating current. As here shown, the battery 6 is in connection with a trickle charger 6a.

25 In Figure 1a reference numeral 1 designates a burglar alarm circuit in connection with a set of dry cells 6b. The circuit 1 is adapted to be closed when the various doors, windows and so forth, interposed in series therein are closed.

30 The door and window switches may be of any standard form and one is indicated by way of example at 6c. The coil of a relay 2 is included in circuit 1 and when the coil is energized, which is the condition contemplated in Figure 1a, contacts 3a of the relay are closed and contacts 3 are open. The armature of the relay is indicated at 3b. With contacts 3a closed and all other devices of the burglar circuit in protective condition, the burglar circuit is in its normal closed 40 condition.

45 Contacts 3 are connected by wires 4 and 5 through battery 6 and a normally closed thermal switch 8 with the motor terminals of unit 1. A motor 12 is adapted to be driven from converter 45 7 through wires 13 and 14. Mounted on the shaft of motor 12 in insulated relation to the motor, are a pair of conductive discs 15 and 15a of which the former has a series of peripheral teeth 16 formed at intervals, each series of teeth being designed in accordance with a predetermined code. Disc 15a is formed as an eccentric and both it and disc 15 are in connection through wire 15b with the grid of transmitter tube 31. A contact 17 is disposed for engagement by the teeth 16 and is connected by a wire 17a and a

wire 5a, to be hereinafter described, with a common conductor 17c, so that a circuit is completed between conductor 17c and filament 32 of the tube 31, oscillations being thus allowed to pass through this tube.

Reference numeral 63, Figure 1a, designates a fire alarm circuit in connection with battery 6b and having interposed therein a normally open thermostat 64. Also included in the fire alarm circuit is a relay 65 which, through an armature 65a, controls the contacts 68 and 69. The fire alarm circuit ordinarily follows the burglar alarm circuit to afford protection coextensive with the latter and, of course, a suitable number of thermostats 64 may be provided in parallel. With the fire circuit open, contacts 68 and 69 are also open, since the coil of relay 65 is not energized. Contacts 69 are in connection with wires 4 and 5 through wires 4b and 5b. Contacts 68 are in connection through wires 5a and 5c with line 17c and the contact 67 respectively, Figure 1, contact 67 being arranged to wipe the edge of disc 15a throughout substantially half a revolution of the latter.

The operation is as follows:

Upon breaking the burglar circuit 1 and consequent de-energization of the winding of relay 2, contacts 3a are broken, making the burglar control circuit inoperative until relay 2 is manually reset. Contacts 3 are closed so that battery 6 is placed in connection with the motor of unit 7 through wires 4 and 5 and thermal switch 8. The generator of unit 7 energizes the transformer 9, thus placing the transmitter in operation, and also starts motor 12 through wires 13 and 14 so that the keying members 15 and 15a are rotated. Contact 17 is then periodically engaged by the points 16 on the periphery of interrupter 15 so that a code signal, which is a burglar signal, is broadcast.

The heat of tube 46 opens thermal switch 8 after a desired time of operation so that operation of the apparatus is arrested.

In case of fire, the closing of circuit 63 by thermal switch 6 causes the coil of relay 65 to be energized, thus closing contacts 68 and 69. Since contacts 69 are in connection with wires 4 and 5, a driving circuit for the motor of unit 7 is established as before. The closing of contacts 68 causes contact 67 and disc 15a to be connected in parallel with contact 17 and disc 15 so that when disc 15a engages contact 67 a long dash is added to or introduced into the signal previously described for burglary, thus changing the character of the signal and denoting fire, thermal switch 8 functioning to stop the apparatus as before described.

From the above it will be evident that intelligible and distinguishable signals are produced by the alarm message producing apparatus in case of burglary and in case of fire.

Referring now to Figure 2, reference numeral 28' designates a crystal oscillator which drives an oscillator tube 47 through a stabilizing resistor 47a. The plate of tube 47 drives inductance 47b which is tuned to resonance by variable condenser 47c. This circuit capacitively drives the grid of a tube 45' through a capacity 47d which in turn drives the plate of tube 45' and inductance 45a which is tuned by a variable capacity 45b. This circuit capacitively drives tube 15' through capacity 45c, tube 15' being the final amplifier which is modulated by tube 47 through transformer 39', the secondary of which impinges the audio frequencies through coil 45d onto the grid

side of tube 15', thus isolating the circuit from the tube 45' through capacity 45c.

Battery 39a furnishes necessary bias for the tube of grid 15'. Tube 47' is driven through 5 transformer 38' by audio frequency current from tube 56' which in turn is supplied with audio frequency energy through transformer 56a from the message producing means to be hereinafter described.

Rectifier 13' delivers plate supply to the final radio frequency amplifier tube 15' through a filter 50', conductors 50a and 50b. A secondary coil of the transformer 12' also furnishes energy to filament of tube 15'.

A rectifier 83 supplies plate current to all other tubes in the transmitter through a filter 83' and the secondary of a transformer 21' supplies the filament current for these tubes.

Transformers 12' and 21' receive alternating current from a rotary converter or motor generator 11', and a motor for driving a sound record turntable 33' also receives alternating current from unit 11' through wires connected to the leads 19' and 20'.

A direct current battery 10' supplies current to the motor of unit 11' and is in turn kept at full charge by a trickle charger 51'.

The burglar alarm circuit 1' includes one or more switches such as indicated at 1x which are closed when the circuit is in protective condition and in this circumstance the coil of relay 3' is energized by battery 2' so that contacts 4' are closed and contacts 17', 29' and 29a are open. When circuit 1' is broken by an unauthorized person entering the protected premises, contacts 4' are opened and the burglar circuit remains open until relay 3' is reset. Contacts 17', 29' and 29a are closed. Contacts 17' in closing, close a battery circuit through wires 8' and 9' and a stop switch 44' adjacent motor turntable 33', thus starting motor generator 11' and causing the transmitter to function, also starting the turntable motor through wires 19' and 20'. Contacts 29' and 29a in closing, close a circuit from a pick-up or reproducer head 32' through wires 30', 31', 34' and 35' so that audio frequency energy is fed into the primary of transformer 56a and a burglar alarm message is thus placed on the air, assuming the sound record disc, to be hereinafter described, is on the turntable 33'.

In case thermostat 41' of fire alarm system 40' closes, as upon the occurrence of fire in the protected premises, the coil of relay 42' receives energization from battery 40a and the relay contacts 43', 47' and 46' are closed. Contact 43' in closing, closes a battery supply circuit through the stop switch 44', thus starting motor generator 11' and placing the transmitter in operation as before. Contacts 46' and 47' feed audio frequency energy from a second reproducer head 48' to the primary of transformer 56a, thus causing a fire alarm message to be transmitted, assuming the sound record to be in place on the table 33'.

The sound record may vary as to form but 65 essentially comprises a sound track or tracks engageable by the needles of the pick-up heads 32' and 48' in such a manner that intelligible and distinguishable signals can be broadcast. The sound record disc 60 shown in Figure 8 comprises 70 inner and outer sound tracks 61 and 62, the former carrying the fire alarm message and the latter the burglar message. With the apparatus set for operation, the record 60 is placed on turntable 33' with the head 32' at the beginning of 75 the sound track or band 62 and with the head

48' at the beginning of the sound track or band 61, so that in case of disturbance of either the fire or burglar circuits or both, the reproducing head or heads will immediately affect transformer 56a. Head 32' is mounted on a tone arm 45' and the latter strikes the closed stop switch 44' when the head 32' has traversed the band 62, thereby opening stop switch 44' so that operation of the apparatus is arrested. The switch 44', pick-up heads and relays may then be reset. It will be understood that arm 45' is adapted to open switch 44' regardless of whether a burglar or fire alarm or both, has been broadcast.

Each sound track is made with alternate active and blank track sections. That is to say, in cutting the sound track 62, for example, a fire message giving the location of the premises is impressed, a suitable pause follows, and then the message is repeated, and so on. The same applies to sound track 61. In case of both fire and burglary on the same premises, both of the pick-up heads will be placed in operative association with the transformer 56a so that both messages will be broadcast. However, due to the intervals between the messages picked up from the two tracks, one message will frequently be broadcast in the interval of the other and vice versa, so that two intelligible and distinguishable messages, one for fire and one for burglary will be alternately broadcast. The embodiment of Figure 2 is particularly important by reason of the fact that it is capable of broadcasting either a burglar alarm or a fire alarm or both.

It will be understood that the described embodiments are illustrative and not restrictive of the invention and that various changes in the form and arrangement of the apparatus are possible without departure from the scope of the following claims.

I claim:

1. An alarm system comprising a transmitter, an automatic alarm message producing means in connection with said message producing transmitter, a protective circuit in connection with

said message producing means, and control means responsive to said circuit between said circuit and said message producing means to place said message producing means in operation when said circuit is disturbed, said message producing means comprising code signalling means including a conductive wheel having peripherally spaced groups of teeth of which each group is arranged in accordance with a predetermined code and including also a contactor for cooperating with said teeth, means for driving said wheel, the operation of last-named means being governed by said control means, a normally open circuit in parallel with said wheel and contactor, and means for closing said circuit whereby to supersede a portion of the code signal which would otherwise be produced, said normally open circuit being also governed by said control means.

2. An alarm system comprising a transmitter, an automatic alarm message producing means in connection with said transmitter, a protective circuit in connection with said message producing means, and control means responsive to said circuit between said circuit and said message producing means to place said message producing means in operation when said circuit is disturbed, said message producing means comprising code signalling means including a conductive wheel having peripherally spaced groups of teeth of which each group is arranged in accordance with a predetermined code and including also a contactor for cooperating with said teeth, means for driving said wheel, the operation of said last-named means being governed by said control means, a normally open circuit in parallel with said wheel and contactor, and means for closing said circuit whereby to supersede a portion of the code signal which would otherwise be produced, said normally open circuit being also governed by said control means, said circuit closing means including a rotary member driven concomitantly with the code wheel.

JAMES O. HOWTON.
